US0D1014930S

(12) United States Design Patent (10) Patent No.: US D1,014,930 S
(45) Date of Patent: * Feb. 20, 2024

(54) SHOE

(71) Applicant: NIKE, Inc., Beaverton, OR (US)

(72) Inventor: Joël Ryp Greenspan, Portland, OR (US)

(73) Assignee: NIKE, Inc., Beaverton, OR (US)

() Term: 15 Years

(21) Appl. No.: 29/892,611

(22) Filed: May 19, 2023

(51) LOC (14) Cl. 02-04

(52) U.S. Cl.

USPC D2/954

(58) Field of Classification Search

USPC D2/896, 900, 902, 904, 906–908, D2/916–924, 925–945, 947–960, 969–979

CLAIM

The ornamental design for a shoe, as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken lines depicting the remainder of the shoe form no part of the claimed design.

1 Claim, 3 Drawing Sheets
